UNITED STATES PATENT OFFICE.

GEORGE I. CHITTENDEN, OF LAKEWOOD, OHIO.

HANGER FOR WALL-RADIATORS.

1,280,397.

Specification of Letters Patent.

Patented Oct. 1, 1918.

Application filed December 17, 1917. Serial No. 207,486.

To all whom it may concern:

Be it known that I, GEORGE I. CHITTENDEN, a citizen of the United States, residing at Lakewood, in the county of Cuyahoga and State of Ohio, have invented a certain new and useful Improvement in Hangers for Wall-Radiators, of which the following is a full, clear, and exact description.

This invention relates to a hanger for wall radiators, and in certain respects is an improvement over the construction shown in my prior Patent No. 1,172,582, granted February 27, 1916.

The principal object of this invention is to simplify and reduce the expense of the hanger of my prior patent, and particularly to eliminate the necessity for forgings without in the least decreasing the supporting strength of the hanger.

The invention may be briefly summarized as consisting in certain novel details of construction and combinations and arrangements of parts which will be described in the specification and set forth in the appended claims.

In the accompanying sheet of drawings, Figure 1 is a side view of a radiator hanger attached to a wall, and with a radiator indicated in outline; Fig. 2 is a side view on an enlarged scale, with parts in section, of the hanger shown in Fig. 1; Fig. 3 is a front or face view of the hanger with parts in section; and Fig. 4 is a transverse sectional view substantially along the line 4—4 of Fig. 2, looking in the direction indicated by the arrows.

A hanger constructed in accordance with my invention, comprises a bracket 10, which is designed to be secured by expansion bolts 11 or equivalent securing means 11, to a wall 12. This bracket has face portions 10^a and 10^b, the former located near the top of the bracket and the latter at the bottom of the bracket, these portions bearing against the wall 12 as shown in Fig. 1. The bolts 11 pass through openings 10^a and 10^b of these face portions, one opening, preferably the upper opening being elongated vertically, and the other opening being elongated laterally so that the hanger can be properly positioned on the wall even though there should be some slight error in the location of the bolt holes in the wall.

The bracket 10 is provided at its upper end with a forwardly projecting ear 10^c, having a vertical opening 10^d, and terminat-

ing in a front down-turned lip 10^e having a laterally or transversely elongated opening 10^f. Additionally the bracket is provided near its lower end with a lower forwardly projecting ear 10^g having a vertical opening 10^h which is in alignment with the similar opening 10^d in the upper ear 10^c. The ear 10^g is further provided at its front edge with a notch 10ⁱ.

The radiator is supported from the upper ear 10^c of the bracket by a plain bolt 13 having at its upper end a head 13^a which rests on the top of the upper ear 10^c, the bolt passing freely through the opening in the lower ear 10^g. The lower part of the bolt is threaded to receive a nut 13^b. The supporting means includes in addition to the bolt 13, and nut 13^b, a substantially L-shaped lower radiator seat 14, having a laterally projecting portion 14^a on which the radiator rests, this portion being below the ear 10^g of the bracket, and an upright portion 14^b which extends upwardly past the ear 10^g, and terminates in an inwardly projecting portion 14^c, having an opening through which the bolt 13 loosely passes. The inwardly projecting portion has on its under side a recess 14^d shaped to receive or accommodate the nut 13^b and to hold it against turning when the bolt 13 is turned.

The seat 14 is provided along the bottom and rear sides of the lower and upright portions respectively, with a strengthening rib 14^e which enters the notch 10ⁱ in the lower ear of the bracket so as to prevent any lateral swinging movement of the seat with reference to the bracket 10 and bolt 13.

The radiator which is indicated in outline in Fig. 1 and is designated 15, will rest on the lower portions 14^a of the seats 14 of two or more hangers such as described, and will be held against the upper lips 10^e of the brackets by short bolts 16, one of which is provided near the top of each hanger, this bolt passing through the laterally elongated opening 10^f in the lip 10^e and through or between the arms, not shown, of the radiator, and provided at its forward end with a suitable abutment in the form of a washer 16^a which engages the radiator. It might be mentioned at this point that this laterally elongated opening 10^f allows the necessary longitudinal movement of the radiator relative to the bracket under the action of expansion or contraction.

Both the bracket 10 and lower radiator

- seat can be formed of castings such as malleable iron or gray cast iron, and as the remainder of the hanger, including the bolt 13, and short upper bolt 16 with its washer 16^a are simple inexpensive members, and as there is practically no machining required in making these parts, it will readily be seen that the cost of the hanger has been reduced to practically a minimum. Nevertheless, this hanger has ample strength, the whole weight of the radiator being carried up to the upper ear of the bracket 10, this portion being made of sufficient thickness to support the radiator with an ample factor of safety.
- Inasmuch as the bolt 13 passes loosely through both ears of the bracket and loosely through the upper end 14^c of the seat 14, and as the seat supporting nut 13^b is held from turning on the bolt, the radiator can be adjusted vertically by simply turning the bolt 13 by a wrench applied to the upper bolt head.
- Having described my invention, what I claim is:
1. A hanger for a wall radiator comprising a bracket adapted to be secured to a wall and having laterally projecting portions, a bolt passing freely through said laterally extending portions of the bracket, a radiator seat having a lower radiator engaging portion and having a portion extending upwardly therefrom and adjustably connected to the bolt between the laterally extending portions of the bracket.
2. A hanger for a wall radiator comprising a bracket adapted to be secured to a wall and having outstanding portions, a bolt passing freely through these portions, a lower radiator seat having a portion adapted to engage the lower part of the radiator and having an upwardly extending part with an opening through which the bolt freely

passes, a nut on the bolt held from turning by the seat and supporting the seat, said nut being located between the outstanding portions of the bracket. 45

3. A hanger for wall radiators comprising a bracket adapted to be secured to a wall and having laterally projecting ears, a bolt passing freely through said ears, a radiator seat having a radiator engaging portion beneath the lower ear, and having a portion extending upwardly past the lower ear and adjustably supported on the bolt between the ears, the upwardly extending portion of the 55 seat and the lower ear having interfitting guiding portions.

4. A hanger for a wall radiator comprising a bracket having upper and lower outwardly projecting ears, a bolt passing freely 60 through the ears and provided with an adjustable nut between the ears, a radiator seat having a lower portion which is beneath the lower ear of the bracket, an upstanding portion which extends past the lower ear, and an 65 inwardly extending portion through which the bolt passes, and which rests on said nut, the upwardly extending portion of the seat and the lower ear of the bracket having interfitting portions. 70

5. A hanger for a wall radiator comprising a bracket having outwardly extending ears, the upper ear terminating in a down-turned lip, constituting a side bearing portion for the radiator, a bolt extending freely 75 through both ears, a lower radiator seat adjustably connected to the bolt between the ears, and means passing through said lip and adapted to extend through the radiator for pressing the radiator against said lip. 80

In testimony whereof I hereunto affix my signature.

GEORGE I. CHITTENDEN.
